(57) CLAIM

The ornamental design for a lip balm container, as shown and described.

DESCRIPTION

FIG. 1 is a front, right and top perspective view of a lip balm container, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right and top perspective view thereof, shown with the lid in an open state.

The broken lines shown in the drawings are included for the purpose of illustrating portions of the lip balm container that form no part of the claimed design.
